H. E. Peck.

Inventor,

James A. Irons.

By his Attorney

O. E. Duffy

UNITED STATES PATENT OFFICE.

JAMES A. IRONS, OF WATER CURE, PENNSYLVANIA.

HOT-AIR GRATE.

SPECIFICATION forming part of Letters Patent No. 393,236, dated November 20, 1888.

Application filed January 18, 1888. Serial No. 261,112. (No model.)

To all whom it may concern:

Be it known that I, JAMES A. IRONS, of Water Cure, in the county of Beaver and State of Pennsylvania, have invented certain new and useful Improvements in Hot-Air Grates; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improvement in hollow hot-air grates.

The object of my invention is to provide means for utilizing the heat which escapes into the open air from open grates and to use said heat in heating air which can be conveyed to various parts of a house by means of suitable conduits or pipes.

A further object is to provide a grate which shall consist of hollow grate-bars connected with a hollow back piece, a hollow top bar in communication with the hollow grate-bars, and hollow side pieces in communication with the back piece and front top bar, said hollow grate being provided with one or more cold-air inlets and with one or more hot-air outlets; and a further object is to provide a hollow grate provided with one or more cold-air inlets, one or more hot-air pipes connected with said grate and adapted to convey the heated air to any desired portion of a house or dwelling, and a hot-air pipe adapted to conduct the heated air to a hot-air chamber, whereby the water in a suitable reservoir is heated.

With these ends in view my invention consists in certain novel features of construction and combinations of parts, more fully described hereinafter, and particularly pointed out in the claims.

Referring to the accompanying drawings, Figure 1 is a section of part of a house through a portion of two stories, showing the grate, pipes, &c. Fig. 2 is a top horizontal section of the hollow grate. Fig. 3 is a side view of one of the side pieces, and Fig. 4 is a perspective view of the water-reservoir and hot-air pipe connected with the same.

In the drawings, the reference-letter A rep-

resents the outer wall of any suitable building provided with the usual flue or chimney, *a*.

B represents a hollow grate, preferably located in a fire-place upon the lower floor of the building, so as to be in communication with the flue *a*. The hollow grate *B* is composed of a hollow back piece or casting, *b*, which is intended to fit into the wall at the back of the fire-place, and is provided at its rear bottom portion with an opening into its hollow interior, into which opening extends the inner end of a cold-air-supply pipe, *b'*, preferably passing through the outer wall of the building and communicating with the outer air, and the cold air passing through said pipe into the grate can be regulated in its flow by means of a suitable damper or valve, *b''*, as shown in Fig. 1.

The lower end of the back piece or casting is provided with a laterally and outwardly extending hollow flange or projection, *b³*, provided with a series of apertures in its outer vertical edge, into which apertures are adapted to fit and extend the lower ends of hollow grate-bars *c*, the interiors of which communicate with the interior of the hollow back piece, and said grate-bars curve outwardly and upwardly from the flange on the back piece and open into the lower edge of a hollow front bar or casting, *c'*, which extends across and forms the front top of the grate. The ends of the grate are closed by the hollow end pieces or casting, *d d'*, one for each end, which are curved at their front edges to conform to the curvature of the grate-bars, and at the rear edge of their inner sides or faces the end castings are each provided with the opening *d''*, which extends from the top of the end piece to its bottom, and then laterally a short distance to admit an end of the back piece or casting, and thus hold the interiors of the back piece and end pieces in communication, as shown in Fig. 2. The two end pieces, the back piece, the front upper bar, and the hollow grate-bars are all preferably cast or constructed separately, and are afterward secured together in any suitable manner, so that their interiors will communicate.

A horizontal diaphragm or partition, *m*, is located a short distance below the upper wall of the interior of the back piece or casting, and forms a chamber, *m'*, in the upper portion

separate from the rest of the interior of the back piece, as shown in Fig. 1. The end pieces are also each provided with a diaphragm or partition, m^2 , in their upper portions, which form a chamber in the upper portion of each end piece cut off from the rest of their interiors, and said partitions m^2 are preferably inclined rearwardly, Fig. 3, and the chambers cut off by the same communicate at their lower front ends with the ends of the interior of the front bar, and at their upper rear ends with the ends of the interior of the chamber m' in the upper portion of the back piece.

It will be observed that the partitions m^2 do not extend the whole length of the end pieces; but at the lower front portions of the same they leave outlets or ports n , opening from the lower interiors of the end pieces into the chambers or flues formed in their upper portions, so that the hot air can pass from the interior of the end pieces into the chambers or flue at the top of the back piece.

One or more hot-air pipes or flues, g g' , (two are shown in the present case,) communicate at their lower ends with the interior of the chamber or flue in the upper portion of the back piece, and are adapted to convey the heated air to any desired portion of the building. The hot-air pipes are preferably secured to the rear side of the chamber m' , and extend upwardly through the walls or flue to the floors above.

A hot-air pipe or flue, f , is secured at its lower end to the front edge of the front top bar of the grate, preferably near one end of the same, (see Fig. 2,) and communicates with the interior of the top bar. The hot-air pipe f extends upwardly from the grate to a hot-air chamber, h , preferably formed by any suitable metallic dish-shaped receptacle, p , which is secured upon the wall of a room a suitable distance below the mantel, by means of a perforated flange or lip, w . The hot-air pipe f passes through the closed bottom of the receptacle, and a water-reservoir, f' , is adapted to removably rest in and close the upper open portion of the receptacle, and thus form the top wall of the hot-air chamber. (See Figs. 1 and 4.) The end of the hot-air pipe f extends a short distance above the bottom of the hot-air chamber h , to prevent water that might leak into said chamber from the reservoir from passing down the hot-air chamber into the grate, and the walls of the hot-air chamber are provided with apertures i , to allow such water to flow out of the chamber, and also to allow the hot air to pass out, so that a continuous circulation of hot air will be kept up through the hot-air chamber. The hot-air pipe can be provided with a suitable valve or

damper, y , to regulate the flow of hot air to the chamber h .

The partition m in the back piece, b , of the grate is preferably located so as to be on the same level as the top of the front top bar. 65

It will be observed that the cold air enters the lower portion of the back piece through pipe b' , and as it becomes heated it passes from the lower portion of the back piece up through the hollow grate-bars and into the hollow end pieces, from thence into the hollow front top bar, and from thence it flows from the front bar rearwardly through the rearwardly and upwardly inclined flues in the upper portions of the end pieces into the chamber m' in the upper portion of the back piece, from whence it can be conveyed where desired. 75

It is clearly evident that numerous slight changes might be made in the form and arrangement of the various parts described without departing from the spirit and scope of my invention; hence I do not wish to limit myself strictly to the precise construction herein set forth, but consider myself entitled to all such slight changes. 80

Having thus fully described my invention, what I claim, and desire to secure by Letters Patent of the United States, is—

1. The combination, with a hollow grate and one or more cold-air inlets, of a hot-air-outlet pipe opening into said hollow grate, a hot-air chamber in communication with the grate by means of the outlet-pipe, and a water-reservoir above the hot-air chamber, substantially as described. 90

2. The herein-described hot-air grate, consisting of a hollow back piece or casting provided with a longitudinal chamber or flue in its upper interior cut off from the lower part of the interior by a partition or diaphragm, one or more fresh-air pipes or inlets opening into the lower interior of said back, hollow end pieces or castings communicating with the lower interior of said back, and provided with flues or chambers in their upper interiors communicating with the upper chamber of the back, a hollow front or top bar communicating with the interiors of the end pieces, hollow grate-bars opening into the lower interior of the back and extending upwardly and opening into the top or front bar, and one or more hot-air-discharge pipes or outlets, substantially as described. 100

In testimony that I claim the foregoing as my own I affix my signature in presence of two witnesses. 110
